UNITED STATES PATENT OFFICE.

HEINRICH SCHULZ, OF WORMS, GERMANY, ASSIGNEE TO FIRM CORNELIUS HEYL, OF WORMS, GERMANY.

METHOD OF TREATING VARNISHED (PATENT) LEATHER.

1,325,415.

Specification of Letters Patent. Patented Dec. 16, 1919.

Application filed December

1916. Serial No. 136,403.

To all whom it may concern:

Be it known that I, HEINRICH SCHULZ, chemist, subject of the German Emperor, residing at No. 57 Alzeyerstrasse, Worms, Germany, have invented certain new and useful Improvements in Methods of Treating Varnished (Patent) Leather, of which the following is a specification.

In treating patent leather and the like with ultraviolet rays which is produced, for example by means of quartz lamps, secondary reactions appear which prevent and delay the proper procedure of the drying process. Ozone which is generated by the light of short wave length from quartz lamps has been recognized as particularly noxious. It has, therefore, been already pointed out in the specification of German Patent 253,309, that such ozone must be removed, if good results are to be obtained. This removing of the ozone is secured by means of ventilation. But a ventilation of the exposure chamber is apt, particularly in summer, on tropically hot days, to introduce moist air into said chamber, and this moist air will, on its part, have an unfavorable effect on the drying of the varnish. For this reason it has been already suggested in the specification of German Patent 284,604 to desiccate the air by refrigerating machines, with the unavoidable result, however, that the leather is subjected to changes of temperature, which have an unfavorable effect on the final product.

Experiments have shown that the quartz lamp will continuously generate ozone at a temperature below 40° Réaumur. If the temperature is raised beyond 40° Réaumur, ozone will be generated at the lighting up of the lamp, but the generation thereof will soon cease. This observation has, now, according to the present invention been utilized for the light treatment of patent leather and the like in such a manner, that the quartz lamps are made to burn in air heated to a temperature above 40°, preferably to 50° Réaumur.

The method is, in practice, preferably carried out in such a manner, that the air is not desiccated by refrigerating plants, but that the atmospheric air which is sucked

in by a fan, is heated to 50° Réaumur. Hereby the air is brought into such a condition that it will no longer give off any moisture, and is even capable of absorbing moisture; in other words, the air is dry. This affords the advantage that the temperature is not subjected to any change during the drying process.

In the accompanying drawing, which illustrates one form of apparatus capable of being advantageously used to carry out the present invention,

Figure 1 is a diagrammatic plan view of the apparatus, the top wall being omitted, and Fig. 2 is a vertical section of the same.

Referring more particularly to said drawing, 1 indicates, in general, the comparatively long, narrow housing or chamber, in which the leather is hung, or through which it is passed and exposed to the action of the ultra violet rays in well known manner. The leather is suitably stretched on frames 2, which run on the tracks 3, 4, 5, 6 arranged in parallel relation along the length of the chamber 1.

Midway of the length of the chamber 1 are suspended the lamps 7, preferably of the mercury vapor type, said lamps being at various heights, as is usual, so as to cause their light to be evenly thrown over the surfaces of the sections of leather.

At the bottom of the chamber 1, is arranged a pipe 8 extending in one direction through the length of the chamber and connected with a heater 9, to which latter there is connected, in turn, a fan or blower 11; and at the top wall of the chamber is arranged a pipe 10 which extends in the opposite direction through the length of the chamber. The air blown into the heater by the fan is heated therein to 50° Réaumur, and is then introduced into the chamber 1 through the pipe 8, which is perforated for that purpose. The pipe 10 is also perforated, and is utilized to suck the heated air from said chamber; and with that object in view, it is connected to the suction side of a fan, which may be, and preferably is, the fan 11. The connection between the fan and the pipe 10 is, however, omitted from the present showing. The further op-

eration of the apparatus is obvious from the description thereof, and need not be particularly set forth.

I claim:

5 The herein-described method of treating varnished leather, which consists in subjecting the leather to the action of light rich in

ultraviolet rays in a closed chamber; and continuously forcing air, previously heated to a temperature above 40° Réaumur, into 10 said chamber and exhausting it therefrom.

In testimony whereof I affix my signature.

HEINRICH SCHULZ.
